UNITED STATES PATENT OFFICE.

WILLIAM H. GOLDER, OF PORTLAND, OREGON.

DEVICE FOR OPERATING ELEVATOR-GATES.

SPECIFICATION forming part of Letters Patent No. 439,940, dated November 4, 1890.

Application filed July 18, 1890. Serial No. 369,130. (No model.)

To all whom it may concern:

Be it known that I, WILLIAM H. GOLDER, of Portland, in the county of Multnomah and State of Oregon, have invented a new and Improved Elevator-Gate, of which the following is a full, clear, and exact description.

My invention relates to improvements in that class of elevator-gates that are used to close the entrances to the elevator-well and that are automatically operated by the movement of the elevator-car.

It has been the practice in operating this class of gates to have them both raised and lowered by the movement of the car, and consequently if the gate in its descent or ascent met with an obstruction some part of the device would necessarily break. The object of my invention is to obviate this difficulty by producing a gate that will drop of its own gravity, and at the same time be controlled in its descent and to make the connections with the gate in such a manner that nothing will be broken though the gate meet with an obstruction.

A further object of my invention is to produce a gate of simple construction that is cheap and durable, that is constructed without castings that are likely to break, and that may be easily put in order by an unskilled person in case any of its parts become disarranged.

To this end my invention consists in certain features of construction and combinations of parts, which will be hereinafter fully described, and specifically pointed out in the claim.

Reference is to be had to the accompanying drawings, forming a part of this specification, in which similar letters of reference indicate corresponding parts in all the figures.

Figure 1 is a broken front elevation of the gate and attachments as applied to an elevator well and car. Fig. 2 is a vertical cross-section of the same on the line 2 2 of Fig. 1. Fig. 3 is an enlarged detailed view showing the elevator-car and the gate-operating mechanism in side elevation with the gate in section. Fig. 4 is a transverse section on the line 4 4 of Fig. 3, and Fig. 5 is a broken detailed view showing the catches for engaging the gate-latches and the devices for releasing the latches from the catches.

The elevator-car A may be of any ordinary construction, having a suitable cross-piece A' at the top of the frame and the side pieces A² 55 of the frame, which move in the slotted side posts D, and thus guide the car. The car A is operated by the cables a, which are attached to the cross-piece A' and extend over the winding-drum C, which is pivoted in the top 60 of the elevator-well B.

I have shown means for raising the elevator-car; but the car may be raised and lowered by any suitable mechanism. The gate E extends horizontally across the entrance to the 65 elevator-well B and moves vertically in the slots f of the supports F. When the gate is in closed position, it rests upon the floor G, and a gate is provided for each floor of the building.

A strip H extends vertically on one side of the elevator-well, said strip being arranged adjacent to one of the side posts D, and the strip is provided with the parallel vertical dovetailed slots h, h', and h², which extend 75 throughout its entire length. Pivoted in the upper portion of the strip H, between the slots therein, are the pulleys i, j, and k, said pulleys being arranged one a little above the other, and the size of the pulleys is such that 80 their faces will be opposite the central portions of the slots. Pivoted in the lower portion of the strip H so as to align with the pulleys j and k are the pulleys j' and k', the said pulleys at top and bottom of the strip H 85 being adapted for the passage of the gate-cables, as described below. A catch L is dovetailed into the slot h so as to move vertically therein, the said catch projecting from the face of the strip H so as to engage the gate-operating latches, as described below, and a similar catch L' moves in the slot h', the said catches being connected with the gate-operating cable, as hereinafter described. The cable M is fixed centrally to the upper portion 90 of the gate E, said cable being composed of two strands or members M', which extend upwardly over the pulleys m, which are pivoted to the support b near the upper part of the story, and the said members M' thence turn 100 at right angles and pass over the pulleys n, which are pivoted to a suitable support near the upper corner of the elevator-well, and one of the said members M' passes over the pul-

ley i and thence down the slot h to the catch L , to which it is attached. The other member M' passes over the pulley k and thence down the slot h^2 , over the pulley k' , and thence up the slot h' to the catch L' , to the lower end of which it is attached. A cord or cable M^2 is attached to the upper end of the catch L and extends upwardly through the slot h in the strip H , over the pulley j , and thence down the slot h' to the catch L' , and is fixed to the upper end of the said catch. A cable M^3 is fixed to the lower end of the catch L and extends downward in the slot h , over the pulley j' , and thence up through the slot h' to the catch L' , and is fixed to the lower end of said catch. It will thus be seen that the various cables form practically a continuous cable extending from the elevator-gate E around the pulleys, as described above.

20 A projection O is fixed to the front of the strip H on the outer side of the slot h , said projection having inclined ends that it may easily engage a latch, and a similar projection O' is fixed to the strip H between the slots h' and h^2 , said projection having inclined ends like those of the projection O , and the projections O and O' are fixed in relation to each other, so that as one latch passes off from one of the projections the opposite latch 30 will engage the other projection. This operation will be more fully described below.

A plate P is fixed to the top A' of the elevator-car and projects at right angles to said top so as to extend opposite and parallel 35 with the strip H . The plate P is provided on its lower edge with a projecting portion P' , which aligns with the slot h of the strip H , and upon its upper edge with a projection portion P^2 , which aligns with the slot h' of 40 the strip H , and centrally pivoted on the plate P on the side next the strip H are the latches p and p' . The latch p extends downward opposite the slot h in the strip H , and the latch p' extends upward, aligning with 45 the slot h' in the strip H . The latches p and p' are sufficiently wide to lap the slots in the strips H and to engage the projections O and O' on said strip, and the latches are held normally against the face of the strip H by the 50 springs p^2 , which are arranged between the latches and the plate P , said springs having suitable guides p^3 to hold them in position.

The projections O and O' are arranged between each floor of a building, and when the 55 elevator-car A is below the floor G and the gate E rests upon the floor the catch L will be normally in an elevated position, as shown in Figs. 1 and 2, and the catch L' will be nearly opposite the floor. As the elevator 60 ascends, the latch p' strikes the lower end of the catch L' and raises said catch in the slot

h' . As the catch L' ascends, the catch L will be moved downward by means of its connection with the catch L' , and as the inner ends of the members M' of the cable M are connected with the upper ends of the catch L and with the lower end of the catch L' the outer end of said members will be raised, thus raising the gate E . As the car continues its ascent, the latch p is brought in contact with the projection O , thus raising the latch from the face of the strip H and allowing the catch L to pass beneath the latch. The latch p' then engages the projection O' , thus releasing the latch from the catch L' , 75 and thereby allowing the gate E to drop of its own gravity, and as the gate drops the catch L is moved upward in the slot h and the catch L' moves downward in the slot h' , so that the catches resume their former position. When the car descends, this action is reversed, the catch L being forced downward by the latch p , thus operating the members M' of the cable M and raising the gate E , and the latch is released by the projection O , 85 thereby allowing the gate to drop.

It will be noticed that when the gate drops one of the latches is supported on a catch, thereby allowing the gate to drop with the same speed at which the elevator-car moves, 90 thus preventing the gate from falling too fast.

Having thus fully described my invention, I claim as new and desire to secure by Letters Patent—

The combination, with the car, its guideways, and operating mechanism, of the strip H , having three grooves h h' h^2 in its face parallel with said guideways, the pulleys i j k at the upper ends of said grooves and the pulleys j' k' at the lower end of strip H in vertical alignment with pulleys j k , the inclined projections O O' , arranged as shown, the catches L L' , movable vertically in the grooves h h' , respectively, the vertically-sliding gravity-closing gate, the pulleys m m n n above 95 the gate, the double cable M , passing from the gate over said pulleys and downward over pulleys i k to the upper side of catch L and lower side of catch L' , respectively, the cable M^3 , passing under pulley j' upward to 100 the catches L L' , the cable M^2 , extending over pulley j to the catches L L' , and the plate P , projecting from the car across the strip H and having the two oppositely-projecting spring-catches overlapping the grooves h h' 105 to engage the catches and projections, substantially as set forth.

WILLIAM H. GOLDER.
